UNITED STATES PATENT OFFICE.

WILLIAM H. NICKERSON, OF BROOKLINE, MASSACHUSETTS.

SHOE-SHANK STIFFENER.

Application filed January 19, 1925. Serial No. 3,223.

This invention relates to a metal stiffener, composed of an oblong strip of sheet metal adapted to be interposed between the curved shank portions of an insole and an outsole, for the purpose of preserving the usual curved form of said portions and imparting suitable stiffness with a slight resilience thereto.

In particular the invention relates to a stiffener having integral sole-penetrating spurs, the edges of which are defined by slits cut in the strip, the prongs being bent upward, and adapted to secure the stiffener to the insole, the spurs being spaced from the ends of the stiffener, so that the stiffener has extensions projecting outward from the spurs, and adapted to prevent liability of a prying dislodgement of the spurs from a sole in which they have been inserted.

For the sake of economy of metal, the blank from which the stiffener is made, is oblong and substantially rectangular, and the spur-defining slits are made wholly within the margin of the blank, so that when the spurs are bent upward, notches are formed in the longitudinal edges, and the portions of the strip between the spurs are considerably narrowed and constitute relatively weak necks connecting the major portion of the stiffener with the extensions. Heretofore a stiffener thus characterized has been provided in which the spurs are formed wholly on the extensions and outside the narrow necks, so that bending strain exerted on the stiffener, when the spurs are inserted in a sole, is liable to bend or break the stiffener crosswise at said necks, and break away the spurs from the body of the stiffener.

The object of this invention is to provide a stiffener, the spurs of which are located wholly between the necks and upon the main portion of the stiffener, instead of on the extensions, so that strains transmitted from the main portion to the spurs, or vice versa, are not exerted on the narrow necks.

Of the accompanying drawings forming a part of this specification:—

Figure 1 is a side view of the slotted blank from which the improved stiffener is made.

Figure 2 is a top view, and

Figure 3 an edge view of the completed stiffener.

Figure 4 shows in perspective, and on an enlarged scale, the end portions of the stiffener, the mid-length portion being broken away.

The same reference characters indicate the same parts in all of the figures.

My improved stiffener is struck up from the oblong rectangular blank strip shown by Figure 1. That portion of the stiffener called the body portion, is designated by 12.

Extending inward, from the transverse edges of the strip are slits 13, the inner ends of which are spaced apart by relatively narrow portions 14, which constitute necks in the completed stiffener. The slits define the inner edges of sole-penetrating spurs 16, which are bent upward from the strip. The portion of the strip between the inner ends of the pairs of slits shown by Figure 1, constitutes the main or body portion 12. The spurs 16 are bent from said body portion at the extremities thereof. The end portions 18 of the strip project substantially in line with the body portion between, and longitudinally outward from the bases of the spurs. Said end portions are adapted to bear on an outer sole and prevent prying dislodgement of the spurs from an inner sole in which they are inserted. The usual function of the stiffener is exerted wholly by the body portion 12 and spurs 16.

It will now be seen that the spurs are formed wholly on the body portion extremities from which they project, and that the strength of the spurred body portions is not impaired by the relatively narrow necks 14.

Although I have shown the same formation at each end of the stiffener, it is obvious that this formation may be used only at the forward end, and that the rear end of the stiffener may be otherwise formed and adapted to be secured to an inner sole.

The body portion is longitudinally curved, as shown by Figure 3, and provided with a longitudinal boss forming a longitudinal channel in one side and a ridge on the opposite side, as heretofore. The ends of the boss are spaced from the end portions 18, so that only the body portion 12 is stiffened by the boss.

It will also be seen that the embossed body portion 12 is relatively stiff and more rigid than the end portions 18, which latter have substantially flat surfaces that bear against both the inner and outer soles between which the stiffener is arranged.

Such flat end portion 18 at the forward end of the stiffener being connected with the body portion 12 by the reduced and relatively flexible neck is adapted to conform to

flexure of the outer sole so that its free extremity is not liable to dig into and injure the outer sole.

It is desirable to employ mild basic steel (untempered) as the material of the stiffener, this material being free from liability to be cracked by embossing dies, and differing in this respect from tempered steel.

The location of the spurs wholly on the body portion, permits the employment of untempered steel, without the objections to its flexibility, which would exist if the spurs were formed as heretofore on the end extensions.

15 I claim:—

A shoe-shank stiffener struck-up from an oblong strip of sheet metal of uniform thickness, and provided with a longitudinal stiffening boss, the ends of which boss are spaced from the ends of the stiffener, so that the stiffener has a relatively stiff body por-

tion and substantially flat end portions, the end portion at the forward end of the stiffener being provided with oblique slits extending inward toward the body portion and providing with the outer edges of the stiffener a pair of spurs which are bent from the plane of the body portion, and from the forward end thereof, said slits imparting a tapering form to the said flat end portion, so that the latter is connected with the body portion by a relatively narrow and flexible neck, the flat end portion being adapted to bear on both an inner and an outer sole in advance of the spurs to prevent dislodgment of the spurs from an inner sole and to conform to flexure of the outer sole, to prevent injury to the latter by the extremity of the end portion.

25 30 35 In testimony whereof I have affixed my signature.

WILLIAM H. NICKERSON.
